J. S. MILLARD

DOLL

Filed Feb. 3, 1922

UNITED STATES PATENT OFFICE.

JEAN S. MILLARD, OF AKRON, OHIO.

DOLL.

Application filed February 3, 1922. Serial No. 533,761.

To all whom it may concern:

Be it known that I, JEAN S. MILLARD, a citizen of the United States, residing at Akron, in the county of Summit and State 5 of Ohio, have invented new and useful Improvements in Dolls, of which the following is a specification.

My invention relates to dolls and particularly to dolls having head and limb members that are readily detachable from the body.

Heretofore, it has been the practice to provide dolls having heads and limb members formed integrally with the body or with 15 the head separably connected to the body portion and rigidly secured thereto after attachment. The objection to the dolls with separable heads that were heretofore proposed is that the head is not adjustable relative to the body after it is secured thereto and, therefore, the doll is not as useful as a source of amusement for the child. Furthermore, the limbs of the doll may become mutilated or broken, thus destroying the 20 usefulness of the entire doll. By providing readily separable limb portions, such mutilated parts are quickly replaced and there is no longer reason for discarding the doll. The child is also provided with a toy that 25 may have the arms and legs bent in various positions for its greater amusement and with heads having different facial characteristics, and with members that spring back into position when displaced.

30 A further object of my invention is to provide a soft rubber head covering for the doll that may be drawn over the head to impart different characteristic features to the doll as hereinafter explained in detail.

35 Other advantages of my invention will appear from a detailed description of certain embodiments of my invention as illustrated in the accompanying drawings in which:

40 Fig. 1 shows an assembled doll constructed in accordance with my invention;

Fig. 2 is a side elevation of a separable limb detached from the doll;

45 Fig. 3 shows a limb attached to the doll to permit the doll to assume a seating posture;

Figs. 4 and 5 illustrate two forms of head coverings for attachment to the doll; and

Figs. 6 and 7 are sectional elevational views of modified forms of my invention.

The doll body 1, as shown in the drawings, has a series of sockets 2 that are adapted to receive various body members comprising a head 3, arms 4 and legs 5. Each of the body members has a connecting member that includes a ball portion 6 that is adapted to fit within the corresponding socket 2 to secure the particular member in place.

In order to facilitate the attachment and detachment of the various body members, the body of the doll may be composed of a rubber composition or other semi-elastic material, such as rubber and cork or other 70 substance that provides semi-yieldable openings to the various sockets that will receive the cooperating ball portion 6 of the body members and adjustably secure such members in place, or the body and body members may be formed of a rigid material such as bisque. The body may be chambered or otherwise constructed to obtain a very light structure. When the body is formed of an unyielding material the ball portion 80 of the connection by joining the arms and legs may be formed with any suitable spring arrangement that will permit the ball to be introduced into the corresponding body socket to attach the members to the body. 85 Fig. 2 particularly illustrates a spring ball arrangement that may readily be sprung into an unyielding socket to secure the corresponding arm or leg to the body.

The salient advantages of the above flexible connection are that it permits the ready interchange of the body members by the child so that a number of heads having different facial or racial characteristics, and limbs bent to various positions, may be interchanged by the child, thus obtaining various expressions or postures or other characteristics of the doll which increase its usefulness and educational value as a source 90 of amusement for the child.

95 A head covering 7 of soft rubber is shown detached from the doll in Figs. 4 and 5.

This covering may be formed in any suitable mold that is adapted to impart expression or form to the facial features of the head and is constructed of an elastic composition 5 that permits the covering to be drawn over the head of the doll to thereby greatly change its expression or impart new characteristics thereto.

Fig. 5 shows a soft rubber head covering 10 that is provided with a hat 8 and hair 9 that are cemented or otherwise mounted on the elastic head covering. Such arrangements may embody various forms of hats or other head adornments that the child may readily 15 draw over the head of its doll. The head coverings shown in Figs. 4 and 5 could replace the covering used on the doll shown in Fig. 1.

The advantage of employing separable 20 body members that are also adjustable relative to the body of the doll, will readily be appreciated. For instance, the head may be turned from side to side or nodded, and it will spring back into place if attached to 25 the body as herein provided, head coverings may be used to impart any racial, grotesque, or other characteristic to the face of the doll and the limbs may be bent to any desired position or replaced by other limbs 30 to adapt the doll to the fancies of the child.

Figs. 6 and 7 illustrate connecting members in greater detail. The enlarged ends of the link 10 which is formed of rubber, snap into place in the respective sockets in 35 substantially the same manner as the corresponding ball and socket members of the previously described joints.

Fig. 7 is a more detailed illustration of 40 a rubber connection 11, such as that employed to secure the head of the doll shown in Fig. 1 and which holds the attached member of the doll at greater distance from the body than the previously described joints. Thus a short thick rubber section is provided 45 between articulated parts that affords greater latitude of movement for such parts than is obtained in the other arrangements. This flexible link gives grotesque effects by providing greater freedom of movement of 50 the attached members and by causing those members to spring back into place when displaced by bending the link while still permitting the parts to be moved by twisting the enlarged ends in the confining sockets.

55 The illustrated embodiments of my invention are but a few of the many arrangements that may be employed and details of construction that may be adopted in carrying out the principles of my invention. 60 I, therefore, desire that only such limitations shall be imposed on my invention as are indicated by the spirit and scope of the accompanying claims.

What I claim is:

65 1. A doll comprising a body of semi-rigid

material, a rubber connecting link having enlarged ends, a socket being formed in the body to receive one end of said link, a head having a socket adapted to readily receive the other enlarged end of said link to secure 70 the head in place, said head being thereby removably attached to the body by a ball and socket connection that permits the head to be freely turned and nodded.

2. A doll comprising a body member, a 75 removable head member of substantially rigid material, and a rubber connecting link joining said members, one of said members having a socket formed therein, the other of said members embodying a unitary rubber 80 connecting piece extending therefrom which terminates in an enlarged readily deformable ball portion of rubber formed integral- 85 ly therewith, said head being connected to said body by deforming said ball portion and inserting said ball in said socket, a substantial portion of said rubber connecting piece being exposed between the head and the body of said doll when they are assembled in order that the members may be freely 90 turned and nodded and be resiliently connected.

3. A doll comprising a body having a 95 socket therein, a body member having a socket therein, a flexible connecting link having a ball portion on each end, each ball portion being adapted to be sprung into said sockets to thereby secure said body member to said body in adjustable flexible relation therewith.

4. A doll comprising a head having facial features, and a readily separable soft rubber covering having different facial features and being adapted to be pulled on over 105 said head to change the features of said head, said covering terminating substantially at the shoulders of said doll.

5. An article of manufacture comprising 110 a rubber head covering for a doll having facial features and characters formed thereon and adapted to fit over the head of a doll having different facial features to change the facial features of the doll, said covering being readily separable from the head and terminating substantially at the shoulders 115 of the doll.

6. A doll comprising a body, a head, a rubber connecting link interposed between the head and the body and adapted to 120 separate them, and a thin rubber head covering having facial features adapted to be drawn over said head, said head covering having a neck portion adapted to enclose the exposed portion of said connecting link.

7. A doll comprising a body, a head, a 125 thick short neck of rubber connecting the head and body, and a thin rubber head covering having facial features formed thereon and adapted to stretch over said head, said head covering being adapted to 130

extend to and engage the shoulders of the body.

8. A doll comprising a body having a rubber neck portion, a head adapted to be removably mounted on said neck portion and be thereby spaced from the shoulders of the body, said head having facial features thereon, and a removable thin rubber covering having different facial features and adapted

to be drawn over the head to impart different characteristics thereto, said covering being adapted to entirely enclose the head member and to terminate substantially at the shoulders of the doll.

In witness whereof I have hereunto signed my name.

JEAN S. MILLARD.
